UNITED STATES PATENT OFFICE

143,271

DESIGN FOR A PADLOCK

Francesco Collura, New York, N. Y., assignor to The Eagle Lock Company, Terryville, Conn., a corporation of Connecticut

Application April 11, 1945, Serial No. 118,945

Term of patent 7 years

(Cl. D50—8)

To all whom it may concern:

Be it known that I, Francesco Collura, a citizen of the United States, residing in the city of New York, county of New York, State of New York, have invented a new, original, and ornamental Design for a Padlock, of which the following is a specification, reference being had to the accompanying drawing, forming a part thereof.

The Figures 1, 2, 3 and 4 are the front, top, side and bottom views, respectively, of a padlock embodying my new design.

I claim:

The ornamental design for a padlock, as shown.

FRANCESCO COLLURA.
